UNITED STATES PATENT OFFICE.

MATTHEW IRION AND ADOLF E. MUELLER, OF LOUISVILLE, KENTUCKY.

RECORDING APPARATUS.

1,141,962.

Specification of Letters Patent.

Patented June 8, 1915.

Application filed November 12, 1913. Serial No. 800,761.

To all whom it may concern:

Be it known that we, MATTHEW IRION and ADOLF E. MUELLER, citizens of the United States, and residents of Louisville, in the county of Jefferson and State of Kentucky, have invented a new and Improved Recording Apparatus, of which the following is a full, clear, and exact description.

This invention relates to an apparatus designed for use in connection with automobiles, locomotives and other vehicles for the purpose of indicating the speed of travel at any moment, the daily and total mileage and the time of day, and for making a record of the rate of travel and the times and durations of stoppage.

The general objects of the present invention are to improve and simplify the construction and operation of apparatus of the character referred to so as to be reliable and efficient in use, comparatively inexpensive to manufacture, and so designed as to be thoroughly accurate.

More specifically the invention has for one of its objects to provide an improved recording mechanism of the tape type in which the tape is wound on a spring or other operated reel, the tension of which is opposed by a clock-controlled toothed wheel that perforates and meshes with the tape so as to control the rate of movement thereof in timed relation to the passage of time, the tape being divided into hours and minutes to correspond with diurnal divisions of time, so that it is possible by means of the recording mechanism to ascertain the rate of travel for any minute, and the time, numbers and durations of stoppages of the vehicle. In connection with the tape feeding means is employed a guiding device for engaging the tape with or disengaging it from the toothed feed controlling wheel in the placing of the tape or the removal thereof.

Another object of the invention is the provision of a recording mechanism of the character referred to having a simple and effective marking device in the form of a striking hammer which between successive strokes moves laterally across the face of the recording tape so that transverse rows of markings are made on the continuously moving tape in contradistinction to a single row of marks extending longitudinally of the tape, according to the method of operation of prior devices.

Another object of the invention is to provide a simple, reliable and accurate speed indicating means or speedometer of that type including centrifugally acting elements such as weights whose outward movement is opposed by a series of springs which are brought into action successively as the speed increases, so that at a certain speed only one spring is active, at another speed two springs are active, at a still higher speed three springs are active, and so on until finally all the springs are active in opposing the outward movement of each weight, the weights being of course operatively connected with a needle which passes over a dial to show the speed of travel at any instant. In connection with the speedometer a mileage register is employed for indicating the daily and total number of miles traveled by the vehicle on which the apparatus is mounted.

With these objects in view and others as will appear as the description proceeds, the invention comprises various novel features of construction and arrangement of parts such as will be set forth with particularity in the claims appended hereto.

In the accompanying drawings, which illustrate one embodiment of the invention, and wherein similar characters of reference indicate corresponding parts in all the views, Figure 1 is an enlarged vertical sectional view taken longitudinally of the apparatus; Fig. 2 is a front view of the speedometer section of the apparatus with a portion of the dial broken away to show the needle-operating mechanism; Fig. 3 is a front view of the recording and clock section of the apparatus with the portions broken away; Fig. 4 is a transverse section on the line 4-4 of Fig. 1; Figs. 5 and 6 are detail sectional views on the line a-a, Fig. 4, and looking respectively in the direction of the arrows 5 and 6; Fig. 7 is a sectional view showing the gearing between the clockworks and the winding reel driving spring mechanism; Fig. 8 is a plan view of Fig. 3; Fig. 9 is a front view of the complete apparatus; Fig. 10 is a detail view of the means for laterally moving the marker or hammer step by step; Fig. 11 is a detail sectional view of the hammer actuating means; and Fig. 12 is a detail perspective view of the connection between the counter-balancing means and the needle operating mechanism of the speedometer.

Referring to Fig. 9 of the drawing, it will be observed that the complete apparatus comprises a clock and recording section A and a speed indicating section B which includes mileage registering means. The sections A and B are constructed to form a unitary device which can be suitably mounted on the automobile, locomotive or other vehicle with a flexible driving shaft 1 connected with one of the wheels of the vehicle and with the speedometer. When observed from in front the apparatus appears to contain only a clock 2, in the section A, and a speedometer 3 and register 4 in the section B. The front plate 4^a of the section A is hingedly connected to the front plate 5 by a hinge joint 6, so that the plate 4 can be swung open to permit access to the recording mechanism for the purpose of renewing the record tape each day. A padlock 7 or other equivalent locking means normally holds the front plate or door 4 locked, so that no one can tamper with the recording mechanism.

By reference to Figs. 1, 3 and 8, it will be observed that the minute hand 8 is driven by the shaft 9, which is connected by a train of speed reducing gears 10 with the hour hand 11. The shaft 9 is rotated by a train of gears 12, Fig. 7, from the usual clock spring, not shown, such train of gears being governed by an escapement mechanism 13 of ordinary construction, Fig. 7.

The clock mechanism besides indicating the time of day is operatively connected with an element of the tape feeding means of the recorder, so that the tape will travel in timed relation with the hands of the clock. The recording tape 14 is fed from a spool or reel 15 mounted in the lower right hand corner of the clock section A, and from this reel the tape extends upwardly over and around the platen or rubber roll 16, thence laterally under a guide roller 17, between guide rollers 18 and 19, and thence to a winding reel 20 which is mounted at the upper left corner of the section A. This reel 20 is mounted on a shaft 21 which, as shown in Figs. 7 and 8, has a pinion 22, which meshes with a gear wheel 23 that is suitably mounted and has operatively connected therewith a pinion 24 which meshes with a large gear wheel 25, which gear wheel is driven by a spring 26 arranged within a drum 26^a and adapted to be wound by a key 27 applied to the squared end 27, Fig. 3, of the spring-winding shaft 28, Fig. 7. The rate of feed of the tape 14 is controlled by the clock mechanism through the medium of a toothed wheel 30 which has a pinion 31 meshing with a large gear wheel 32 on the minute shaft 9 of the clock, as shown in Fig. 1. The teeth 33 of the wheel 30 are sharp, so as to puncture the tape 14, which is passed tangentially over the wheel 30, which is disposed between the platen 16 and the guide

pulleys 18 and 19. The toothed wheel 30 which acts as a drag in opposition to the spring 26 for the tape-winding reel makes several revolutions per hour, while the wheel 32 makes one revolution, so that each minute a suitable length of tape will pass over the platen to enable dots or marks to be made on the tape representing the mileage in sixtieths of a mile. The tape, as shown in Fig. 8, is divided into main hour divisions, and each hour division is divided into minute divisions which are numbered consecutively from one to fifty-nine, and between adjacent main sections of the tape are the hour numbers.

In Fig. 8 the number twelve on the tape represents the twelfth hour section, and with the tape in the position shown, the speed of travel of the vehicle between twelve and one o'clock is being recorded, it being understood that the tape is so positioned in the machine that the hour numbers on the tape will agree with the hours of the day. The marking device comprises a hammer 34 which is mounted in the speedometer section B of the apparatus, and operatively connected with the speedometer mechanism so that the numbers of strokes of the marker will vary with the speed of travel. The hammer 34 has a marking point or type 35 so arranged as to make an impression on that portion of the tape 14 that bears on the platen 16. An inking ribbon 36 is interposed between the hammer and tape so that the hammer will press the inking ribbon against the tape and produce an impression, the tape being fed in any suitable manner in synchronism with the operation of the hammer, so that new portions of the tape will be presented to the marking tip.

In placing a tape in the recorder the blank tape will be in the form of a roll applied to the reel 15 which is removably mounted on a shaft or post 15^a fastened to the frame of the section A, there being attached to the reel 15 a milled knob 15^b for conveniently turning the spool in rewinding the tape thereon. The front plate 37, Fig. 3, on the frame of the section A is cut away or provided with a recess 38 so as to facilitate the placing of the spool 15 on the post 15^a or the removal of the spool. After the spool with the tape thereon is placed in position, the tape is unwound and laid over the platen 16 and past the pulleys 17, 18 and 19 to the reel 20, the end of the tape being engaged in a slit 20^a in the reel. The pulleys 18 and 19 are mounted on a lever 39, Figs. 1 and 3, which is fulcrumed at 40 on the frame of the section A, and this lever has a knob 41 which is adapted to be depressed to throw the guide pulleys 18 and 19 upwardly to such a position that the tape will be clear of the teeth 33 on the wheel 30, as shown in Fig. 3 by dotted lines. This is the position of the

pulleys 18 and 19 when the tape is being applied to the recorder. After the tape is fastened to the reel 20 and the latter turned to take up the slack, the member 41 of the lever 39 is raised so as to lower the tape 14 into engagement with the toothed wheel 30, whereby the latter controls the rate of feed of the tape. It will be understood that in applying the tape the time of day will be noted from the clock 2, and that portion of the tape corresponding to the time of day will be placed directly opposite the hammer, and thereafter the tape will move with its hour divisions reaching the platen or hammer synchronously with the hour hand of the clock. To prevent the reel 20 from turning when applying or removing the tape, the shaft 21 for the reel 20 is provided with a ratchet wheel 42 with which a spring-pressed pawl 43, Fig. 3, is adapted to be thrown into engagement by a spring 44. A pawl-releasing device 45 is pivotally mounted adjacent the pawl to disengage the same from the pawl wheel 42. This device 45 is pivoted on a stud 46, and when it is in the full-line position, Fig. 3, the lower end engages the pawl 43 and holds the same released from the reel 42, so that the shaft 21 can turn by reason of the tension of the driving spring 26. When the upper end of the device 45 is thrown to the right, Fig. 3, the pawl 43 engages the wheel 42 and prevents the shaft 21 from turning. The spring 26 is wound by the manufacturer and thereafter will not require winding unless by accident it should unwind completely. When the tape is to be unwound from the reel 20 and rewound on the reel 15, the knob 45 is pressed to the right so that the pawl 43 engages the wheel 42, and when the tape unwinds, the reel 20 will turn clockwise, Fig. 1, and operate through the gearing 22, 23, 24 and 25 to wind the spring 26 so that it regains the tension it lost in previously winding the tape on the reel 20.

Referring now to the speedometer section 13 of the apparatus, it will be observed that a short vertical shaft 50, Fig. 1, is arranged in the bottom of the frame, and to this the flexible shaft 1, Fig. 9, is connected, so that the shaft 50 will rotate as long as the vehicle is in motion. This shaft 50 has a small gear 51 which meshes with a larger gear 52 secured to a sectional vertical shaft 53, there being on the shaft 53 a small bevel pinion 54 which meshes with a large bevel gear 55 fastened to the horizontal shaft 56. This shaft 56 is provided with a pinion 57 that meshes with a gear wheel 58 which carries a finger or projection 59 that serves to operate the hammer 34 of the recording mechanism. This gear wheel 58 is adapted to rotate once for every sixtieth of a mile traveled, this being obtained by suitably adjusting the speed ratio between the shafts 50 and 53, ac-

cording to the circumference of the vehicle wheel to which the apparatus is connected. The hammer 34 is mounted on and fastened to a horizontal shaft 60 and is provided with an arm 61 which extends laterally from the shaft and is disposed in the path of the finger or projection 59 on the gear wheel 58. As the gear wheel 58 turns in an anti-clockwise direction, Fig. 1, the projection 59 engages the arm 61 of the hammer and moves such arm downwardly so that the hammer 34 is moved to the right, Fig. 1, or away from the tape. The projection 59 finally passes out of engagement with the arm 61 of the hammer, so that the latter moves on its striking stroke by reason of the tension of the spring 32, Fig. 4, such spring being coiled on the shaft 60 with one end connected to the hammer, and the other end 63 held fixed.

The hammer 34 is adapted to have a lateral movement so that it will produce a transverse row of impressions from one edge of the tape to the other, and for this purpose the supporting shaft 60 has step by step longitudinal movement. The ends of this shaft 60 are journaled in blocks 64 fastened to a longitudinally slidable shaft or bar 65, the rear block 64 being provided with a lug 66 which is engaged by the bifurcated end 67 of a lever 68. This lever 68 is fulcrumed at one end on a shaft 69, Fig. 1, journaled in bearings 70, and on this shaft 69 is coiled a spring 71 which has its end 72 fastened and its end 73 connected with the lever 68. This lever 68 is provided at an intermediate point with a roller 74 which rides over the stepped surface of an intermittently rotated wheel 75. This wheel, as shown in Fig. 10, has a series of these steps 76, so that in rotating the lever 68 is moved laterally six steps, and when the end of the series of steps is reached, the spring 71 will throw the lever in one sweep to initial position. The stepped wheel moves the hammer 34 step by step to the right, so that rows of marks 77, Fig. 3, will be made on the tape 14, and when the end of a row is reached, the spring 71 will throw the lever 68 to the left and bring the hammer 34 in position to begin the making of another row of marks, it being understood that the tape moves continuously during the marking operation. Intermittent movement of the stepped wheel 75 is effected by a pawl 78 which is pivotally connected with a lever 79 and is adapted to engage teeth 80 on the wheel 75. The lever 79 has one end 81 disposed in the path of the projection or abutment 59 on the gear wheel 58, so that as this wheel 58 turns it will first shift the stepped wheel one step to throw the hammer laterally, and then retract the hammer for the making of a mark on the tape. In other words, a common actuator moves the hammer step by step laterally and causes

the strokes of the hammer. A pawl 82 is used in connection with the wheel 75 to engage the teeth 80 thereof so as to prevent the wheel from turning backwardly as the pawl 78 is retracted. A spring 83 retracts the lever 79 after it has been actuated by the projection 59 on the wheel 58, and a spring 84 holds the pawl 79 in engagement with the toothed periphery of the wheel 75.

10 The speedometer needle or hand 85, Fig. 9, is connected with an arbor 86 which, as shown in Fig. 2, is operated by a train of gears 87 from a swinging arm or lever 88 which is operatively connected with a speed responsive means in turn connected with the vehicle wheel, and in connection with the arbor of the hand a light spring 89, Fig. 2, is employed to hold the hand steady. The arm or lever 88 is connected by a link 90 with another arm or lever 91 approximately parallel with the arm 88 and fulcrumed at 92 on the frame of the machine. A third arm 93 is rigidly connected with the arm 91 to move therewith, there being a roller or equivalent device 94 on the tip of the arm 93, Fig. 1, to engage between the flanges 95 of a sleeve 96 which slides on the vertical shaft 97 of a speed responsive device. The shaft 97 has a pinion 98 which meshes with a gear 99 on a sectional shaft 100, such latter shaft having a gear wheel 101 which meshes with the gear 51. On the upper end of the shaft 97 is fastened a block 102 on which are pivoted hanging weights 103 that are disposed at opposite sides of the shaft 97. The lower extremities of the weights are connected by links 104 with the sleeve 96, so that as the weights move outwardly under centrifugal force, the sleeve 96 will be raised 40 so as to operate through the system of levers 92, 91, and 88, to throw the hand 85 of the speedometer over the scale to indicate the speed at which the vehicle is traveling. The inertia of the weights 103 is sufficient opposition to centrifugal action for a range of movement corresponding to the travel of the speedometer hand over ten miles of the scale, but beyond this point the opposition to centrifugal action is obtained by a series of U-shaped springs 105 which are arranged in front and rear groups and fastened to arms 106 extending forwardly and rearwardly from the block 102. The springs 105 are so arranged that their tips are separated from one another so that the springs act successively against the outward movement of the weights, said weights having laterally-projections or abutments 107 so arranged as to engage the tips of the innermost springs, and after the tips of the innermost springs have been moved a certain distance they engage the springs of an adjacent spring so that after both springs offer outward resistance to both weights, and after moving still farther, a third spring continues its resist-

ance, and so on until finally all the springs are acting against the weights. For instance, after the speed has reached ten miles per hour the first spring begins to act against the weights, and as soon as the speed reaches twenty miles per hour the first and second springs combined act against the outward movement of the weights, and when the speed is thirty miles an hour the first three springs offer resistance to the weights, and so on until the springs are in action.

The mileage registering mechanism C is located in the bottom portion of the speedometer section A of the apparatus. In the lower portion of the speedometer dial or face, as shown in Figs. 2 and 9, are two rows of apertures 110 and 111 through which are exposed dials 112, 113, respectively; the upper row of number wheels serving to indicate the daily mileage and the lower number wheels serving to indicate the total mileage the vehicle has traveled since the installation of the instrument on the vehicle. Each shaft 114 of the upper number wheel 112 has a star wheel 115 with ten ratchet teeth, and cooperating with each ratchet wheel is a pawl or holding device 116 in the form of a pivoted arm having a roller 117 which is maintained in engagement with its adjacent ratchet wheel 115 by a spring 118 pressing on the arm 116, as clearly shown in Fig. 6. The first ratchet wheel *c* has a tooth or pin *t* which upon one rotation of the wheel *c* engages a tooth of one of the teeth of the next wheel *c'*, so as to move the latter one-tenth of a revolution. This ratchet wheel *c'* is also provided with a pin or tooth *t'* which in one revolution of the wheel *c'* engages a tooth of the next wheel *c''*, so as to turn the same one-tenth of a revolution. A tooth *t''* on the wheel *c''* in a like manner engages a tooth of the ratchet wheel *c''*, so as to turn the same one-tenth of a revolution with every revolution of the wheel *c''*. The first number wheel 112, that is to say, the one connected with the ratchet wheel *c*, indicates the distance traveled in tenths of a mile, the second wheel in units of miles, the third wheel in decimals of miles, and the fourth wheel in hundredths of miles, the number wheels being indicated by dotted lines in Fig. 6. The trains of ratchet wheels are actuated by some moving part of the speedometer. The shaft 58^a on which the gear wheel 58 is mounted has at its front end a pinion 119 which meshes with a large gear wheel 120, Fig. 5, there being on this gear wheel a projection 121 which, as the gear wheel rotates, engages once in each revolution an arm 122, Fig. 6, of a pawl-carrying lever 123, such lever being normally held raised by a spring 124 and maintained against a stop 125. The lever has pivoted on its free end a depending pawl 126 which engages the first star wheel *c* of

the mileage registering mechanism, the pawl 126 being yieldingly held against such star wheel by a leaf spring 127 which is fastened on the lever 123 and is operatively connected with the pawl 126. As the arm 122 is engaged by the projection 121 on the wheel 120, the arm moves downwardly until the projection passes out of engagement with the arm, when the latter swings upwardly by reason of the tension of the spring 124. During this movement of the arm 120 the pawl-carrying lever 123 moves back and forth a distance equivalent to one tooth of the star wheel *c*. The lower set of number wheels 113 for the total mileage registry is also provided with star or ratchet wheels *d*, *d'*, *d*², *d*³, respectively, which are turned one by another in the manner described in connection with the upper set of star wheels. The wheel *d* receives rotation from the star wheel *c* just above it, there being a projection 128 on the wheel *c* so as to engage a tooth of the wheel *d* each time the wheel *c* makes a revolution, and consequently the first number wheel of the lower set will indicate miles instead of tenths of miles as does the first wheel on the upper set of number wheels, and as there are four number wheels on the lower set it is possible to register as high as 9,999 miles. Holding pawls like the pawls 113 for the upper set of star wheels are dispensed with for the lower set, as each lower wheel has a frictional spring 129 on its shaft, clearly shown in Fig. 4, so as to press against the star wheel and prevent free rotation thereof.

The system of levers 88, 91 and 93 and sleeve 96 are counterbalanced by a weight 130 on a lever 131, which as shown in Figs. 11 and 12, has a slotted end 132 which overlaps an arm 133 on the shaft 92, the arm 133 having a pin 134 which engages in the slot 135 of the lever 131.

From the foregoing description taken in connection with the accompanying drawings, the advantages of the construction and method of operation will be readily understood by those skilled in the art to which the invention appertains, and while we have described the principle of operation, together with the apparatus which we now consider to be the best embodiment thereof, we desire to have it understood that the apparatus shown is merely illustrative and that such changes may be made when desired as are within the scope of the appended claims.

Having thus described our invention, we claim as new and desire to secure by Letters Patent:

1. In a speed recording apparatus for vehicles, the combination of a tape-holding spool from which a record tape unwinds during recording and on which the tape is adapted to be rewound, a spool on which the tape winds during recording, a mecha-

nism for turning the last-mentioned spool, a clock-operated device for controlling the rate of movement of the tape, and guiding means constantly engaging the tape and mounted adjacent the said device adapted to be manually actuated to release the tape from the said device and hold it released while the tape is rewound on the first-mentioned spool.

2. In a speed recording apparatus for vehicles, the combination of a supporting body, a spool mounted on the body and on which a record tape is adapted to be wound, a tape-holding spool removable mounted on the said body and from which the tape unwinds during recording and on which the tape is adapted to be rewound after recording, means for turning the first-mentioned spool to wind the tape thereon, a clock-operated device engaging the tape during recording to time the movement of the tape, and a lever mounted on the body and arranged to engage the tape for releasing the latter from said device during the rewinding of the tape on the second-mentioned spool, said lever having a handle which is adapted to be held by one hand to maintain the tape released from the said device while the other hand actuates the first-mentioned spool to rewind the tape.

3. In a speed recording apparatus for vehicles, the combination of a clock mechanism, a record tape feeding mechanism, a toothed wheel geared to the clock mechanism to rotate in timed relation therewith and arranged to mesh with the tape, and a device for throwing the same into and out of engagement with the said wheel for permitting the removal or insertion of the tape, said device including means constantly engaged with the tape and on which the tape passes.

4. In a speed recording apparatus for vehicles, the combination of a pair of reels for the record tape, means for driving one of the reels to wind the tape thereon from the other reel, means for turning said other reel to wind the tape thereon, a clock mechanism, a wheel connected with the clock mechanism to rotate therewith and having sharp teeth arranged to perforate the tape and control the rate of feed thereof, a lever, and means mounted on the lever and constantly engaging the tape for moving the latter into and out of engagement with the said wheel for permitting the rewinding of the impressed tape and the insertion of a new tape.

5. In a speed recorder for vehicles, the combination of a tape carrying reel, a driven reel on which the tape winds, a clock mechanism, a toothed wheel driven by the clock mechanism and having its teeth arranged to perforate the tape and control the rate of feed thereof, and a movable device mounted

in fixed relation to the toothed wheel and constantly engaging the tape between the toothed wheel and the driven reel for moving the tape into and out of engagement 5 with the toothed wheel.

6. In a speed recording apparatus for vehicles, the combination of an impression producing element, a support forming the axis for the element and movable axially, 10 a stepped wheel movable step by step, a lever engaged with the wheel to be moved step by step thereby, a connection between the lever and said support to move the latter step by step in the direction of its axis, 15 whereby the said element produces rows of impressions, means for swinging the element back and forth to produce impressions, and means for returning the support to initial position after the row of 20 impressions has been made.

7. In a speed recording apparatus, the combination of a swinging hammer, means for mounting the hammer to move laterally, mechanism for moving the hammer laterally 25 step by step in one direction, means for returning the hammer in one step, a member connected with the hammer for moving the same away from striking position, means for moving the hammer on its striking 30 stroke, a swinging member for actu-

ating the said mechanism, and a rotating element movable into engagement with the member of the said mechanism to actuate the same and into engagement with the member of the hammer for actuating the latter.

8. In a speed recording apparatus, the combination of a swinging hammer, means for supporting the hammer to move laterally, a lever connected with the said means 40 for moving the hammer laterally, a stepped wheel engaging the lever for moving the same step by step in one direction, means for moving the lever in the opposite direction to initial position, a pawl for moving the stepped wheel step by step, a spring connected with the hammer for moving the same on the striking stroke, a member on the hammer, and a rotating device arranged 45 to actuate the pawl and to engage the arm of the hammer for moving the same against the tension of the said spring.

In testimony whereof we have signed our names to this specification in the presence of two subscribing witnesses.

MATTHEW IRION.
ADOLF E. MUELLER.
